UNITED STATES PATENT OFFICE.

JAMES W. WILLING, OF NANTICOKE, MARYLAND.

SPARK-ARRESTER.

1,111,816.

Specification of Letters Patent. Patented Sept. 29, 1914.

Application filed January 21, 1914. Serial No. 813,543.

To all whom it may concern:

Be it known that I, JAMES WARE WILLING, a citizen of the United States, residing at Nanticoke, in the county of Wicomico and State of Maryland, have invented certain new and useful Improvements in Spark-Arresters, of which the following is a specification, reference being had to the accompanying drawings.

10 This invention relates to new and useful improvements in spark arresters and more particularly to a device of the above class which is adapted for application to smoke stacks of locomotives or other stacks of similar character, the main object of the invention being to provide a device of this character which may be quickly and readily applied to the top of the smoke stack for receiving the cinders and other particles 15 passing from the stack and to convey them downwardly and out beneath the engine bed to any desired place.

Another object of the present invention is the provision of a spark arrester of the 20 above character which will possess advantages in points of efficiency and durability, is inexpensive to manufacture and, at the same time, is simple in construction and operation.

30 With the above and other objects in view, the invention consists in the novel features of construction, combination and arrangement of parts as will be hereinafter referred to and more particularly pointed out 35 in the specification and claims.

In the accompanying drawings forming a part of this application, Figure 1 is a side elevation of a spark arrester constructed in accordance with my invention. Fig. 2 is a 40 vertical sectional view; and Fig. 3 is a horizontal sectional view taken on the line 3—3, Fig. 1.

45 Referring more particularly to the drawings, 1 indicates a smoke stack of any general construction, to the upper end of which my improved spark arrester is to be removably applied.

The spark arrester in itself consists of a 50 hood or cowl, as generally indicated by the numeral 2 and is formed of a fine mesh screen wire of a suitable size, so that the same will fit various sizes of stacks. The lower end of the hood 2 is preferably cut so that the same is disposed at an angle, as indicated at 3 and secured to the lower edge 55 of the hood, is a resilient trough 4, to the

upper and outer edge of which is secured the lower edge of the hood, as indicated by the numeral 5, the same being secured preferably by rivets or other similar fastening means. 60

The trough 4 is preferably constructed of resilient metal so that when the hood is applied to the smoke stack, the inner edge of the trough may be curled upwardly and bent inwardly and is of sufficient resiliency so that the same may be applied to stacks of various sizes, the inner edge being curved according to the size of the stack. 65

The trough 4 communicates at the lowest 70 point of the inclination 3, with a drain pipe indicated by the numeral 6, and which is to extend downwardly and open, if applied to a locomotive smoke stack, beneath the body of the locomotive, so that the cinders may 75 be conveyed to the track bed. The hood 2 is further supported in position by means of the standards 7, the lower ends of which are riveted or otherwise secured to the trough 4 and the other ends thereof secured in any 80 suitable manner to the upper ends of the hood. From this, it will be seen that the standard 7 may be retained in an upright position, so as to securely retain the hood 85 in its effective shape.

From the above description taken in connection with the accompanying drawings, it will be readily apparent that I have provided a spark arrester which may be readily applied to smoke stacks of various sizes and 90 which will, at the same time, arrest cinders and sparks and convey them to the road bed or any other desired place. 85

It will also be apparent that my device can be quickly and readily applied to smoke 95 stacks of various sizes and retained in such position by means of the resilient trough 4. The hood 2 will also be supported in its effective position by means of the drain pipe 6. This pipe is preferably formed in sections, telescopically engaged, so that the hood may be readily removed and placed upon the smoke stack without interfering with the position of the drain pipe. 100

It will also be apparent that I have provided a simple and durable spark arrester which is extremely simple in construction and can be manufactured and placed on the market at a comparatively small cost. 105

While I have shown and described the 110 preferred form of my invention, it will be obvious that various changes in the details

of construction and in the proportions may be resorted to for successfully carrying my invention into practice without sacrificing any of the novel features or departing from 5 the scope of the appended claims.

Having thus described this invention, what I claim is:—

1. A device of the class described including a hood provided with an opening adapted to receive a smoke-stack, and a resilient flange around said opening adapted for engagement with the stack, as and for the purpose set forth.

2. A device of the class described including a hood having an opening adapted to receive a smoke-stack, and a resilient flange arranged around said opening, whereby

when the stack is placed within said opening, the inner edge of the flange will resiliently engage the stack to retain the hood in 20 position thereon.

3. A device of the class described including a hood having an opening therein adapted to receive a smoke-stack, and a resilient flange around said opening and 25 adapted to engage the smoke-stack, whereby various sizes of stacks may be disposed within said opening.

In testimony whereof I hereunto affix my signature in the presence of two witnesses. 30

JAMES W. WILLING.
